UNITED STATES PATENT OFFICE.

ARTHUR MILLER, OF COLUMBUS, OHIO, ASSIGNOR TO SOLAR-STURGES MFG. CO., A CORPORATION OF ILLINOIS.

CONTAINER OR CAN.

Application filed January 28, 1921. Serial No. 440,659.

To all whom it may concern:

Be it known that I, ARTHUR MILLER, a citizen of the United States of America, residing at Columbus, in the county of Franklin 5 and State of Ohio, have invented certain new and useful Improvements in Containers or Cans, of which the following is a specification.

My present invention relates to containers or cans, and more particularly to a container especially adapted to ice packed perishable goods in cartons, my object being the provision of a strong, rigid and durable construction which may be quickly and economically 15 assembled and which is reinforced and strongly braced in such manner that when fully assembled the body of the can may be hot galvanized to eliminate all cracks, seams and crevices which might otherwise collect 20 dirt, moisture and the like and cause rusting of the can.

A still further object is to reinforce the can by means of separate reinforcing members readily associatable with the body in 25 such manner as to subsequently permit of hot galvanizing and to also reinforce the can body in such a way as to serve an additional function in preventing close contact 30 of cartons therein with the wall of the body. To the above end my invention proposes a can or container which may be given various forms and which I have shown of rectangular form in the accompanying drawing, forming a part of this specification, and 35 wherein,

Figure 1 is a perspective view of the can with the cover in place,

Figure 2 is an enlarged vertical section through one side of the can,

Figure 3 is a horizontal section, and

Figure 4 is an enlarged detail section through a portion of one of the reinforcing strips.

Referring now to these figures and particularly to Figures 1 and 2 my invention proposes a container including a body 10 and a flanged telescoping cover 11 adapted to close one open end of the body and preferably having its flange 12 terminating at its 50 free edge in a gripping bead 13 as particularly seen in Figure 2.

The invention relates more particularly however to the construction of the can body 10, one end of which is closed by a bottom plate 14 and the opposite ends of which are

reinforced by external surrounding reinforcing strips 15 and 16, each terminating at its inner edge in a semicylindrical bead 17 opening toward the can body and the free edge of which extends slightly beyond the inner surface of the strip as seen by reference to the detail Figure 4 of a portion of the strip 16, thus adapting this slightly elongated free edge 18 of each bead to closely and evenly engage the external surface of the can body 10 particularly in view of the fact that each of the strips is spot-welded as indicated at 19 to the can body immediately adjacent its bead 17.

The outer edge of the strip 15 around the open end of the can has a reverting flange 20 interengaged within a double flange 21, 22 of the can edge so that by pressure the reinforcing strip 15 is thus securely locked in place, the flanges being turned outwardly of the body 10 so that provision is thus made for effective engagement of the cover with its flange 12 and beaded edge 13 as previously described.

On the other hand the strip 16 at the lower closed end of the body 10 is formed by a reverting extension of the depending flange 23 of the bottom plate 14, the lower edge of the body 10 being received between flange 23 and its extension forming the reinforcing strip 16 so that the spot-welding 19 not only holds the reinforcing strip 16 but securely anchors the bottom plate 14 in place.

The body 10 may be bent to form from a single strip of metal with its flanged edges joined in a vertical seam 24 as shown in Figure 3, and is provided therearound with vertically disposed beads 25 which are pressed inwardly so that they not only serve to reinforce that portion of the body between the external reinforcing strips 15 and 16 but they also form inwardly presented ribs which serve to prevent close contact by internal packed cartons and the like with the wall of the body. This structure holds the cartons away from the wall of the body and permits air spaces between the cartons and the walls of the container.

It is thus seen that my invention provides a container particularly adapted for the purposes stated, as well as one which may be readily assembled, which is of a simple economical nature, and which will be strong and durable in use, and it is further ob-

vious that by virtue of the particular manner in which the external reinforcing strips are joined to the body of the container and their free beaded edges forced into close uniform external contact, the completed container in the assembled form shown in the several figures is especially adaptable to hot galvanizing entirely thereover in order to avoid subsequent rusting and the collection of dirt and moisture tending toward this result.

I claim:

A container, comprising a body portion, and a bottom portion having an inner an-

nular down-turned flange extending into an outer upturned flange between which the lower edge of said body portion is disposed, said outer flange terminating in an out-bent bead, the free edge of which contacts with said body portion, said outer flange being permanently attached to said body portion, as by spot-welding, at the junction of said bead with said outer flange, the opposite edge of said bead being unattached to the can body.

In testimony whereof I have affixed my signature.

ARTHUR MILLER.
